UNITED STATES PATENT OFFICE.

CHESTER MAYR, OF CHARTER GROVE, ILLINOIS.

CURRYCOMB.

No. 917,881.

Specification of Letters Patent.

Patented April 13, 1909.

Application filed April 8, 1908. Serial No. 425,941.

To all whom it may concern:

Be it known that I, CHESTER MAYR, a citizen of the United States, residing at Charter Grove, in the county of Dekalb and State of Illinois, have invented certain new and useful Improvements in Currycombs, of which the following is a specification.

This invention relates to curry combs, and more particularly to cleaning attachments therefor and has for an object to provide a device of this character which may be applied to combs of various constructions without material changes thereto, and which will effectively serve to discharge dirt from the brush without hammering the sides of the brush as heretofore.

Other objects and advantages will be apparent from the following description and it will be understood that changes in the specific structure shown and described may be made within the scope of the claims without departing from the spirit of the invention.

In the drawings forming a portion of this specification, and in which like numerals of reference indicate similar parts in the several views, Figure 1 is a plan view of a curry comb showing the application of the present invention thereto, Fig. 2 is a sectional view on the line 2—2 of Fig. 1, Fig. 3 is a sectional view on the line 3—3 of Fig. 2, Fig. 4 is a perspective view of the ejector, Fig. 5 is a view similar to Fig. 2 showing the parts in their operative position.

Referring now more particularly to the drawings, there is shown a curry comb 10 of ordinary construction comprising the usual head 11 and a handle 12 therefor. The head 11 is provided with the usual teeth 13 which are arranged in rows, four rows being shown in the present instance. An ejector member is provided, and consists of a rectangular plate 14 having a plurality of elongated slots 15 which thus receive the teeth 13 of the head, as shown. The plate 14 is disposed beneath the head 11 and is provided with flat springs 16 and 17 respectively slidably connected at their ends to the head by means of studs, as shown in Fig. 3, the studs 18 being passed through slots 18' formed in the springs 16 and 17, and at the center, each spring is provided with a vertically disposed pin 19 each of which is provided with a stem 19'. The pins 19 are disposed upon the springs 16 and 17, the stem 19' passing through the springs to hold them to the plate

14, as shown in Fig. 2. Each of the pins 19 is located in a passage 20 formed in the head 11. The pins have their upper faces beveled as shown at 21 these faces being normally engaged with the beveled portions 22 formed in the under face of a sliding plunger 23 located in a casing 24 carried by the head 11.

The plunger 23 has a portion at the front of the head 11 disposed for movement in a passage 25 formed in the front end of the casing 24, and outwardly of the front end of the casing the plunger is provided with a head 26. Rearwardly of the beveled faces 22, the plunger is cut to provide vertical shoulders 27 which normally lie against the pins 19, the plunger being held with the shoulders in this position by means of a helical spring 28 located within the casing 24 at the rear end thereof and between this end and the plunger. In use, it will thus be seen that upon movement of the plunger 23 within the casing 24 the beveled faces 22 will engage the pins 19 and force the same downwardly, carrying therewith the plate 14 which will effectively serve to eject dirt from between the teeth of the brush. As soon as the plunger is released, it is obvious that the plate 14 will be restored to its normal position by the springs 16 and 17, and by means of the spring 28 the plunger 23 will also be restored to its normal position for further operation of the device.

What is claimed is:

1. In a curry comb, the combination with a head, of depending teeth carried by the head, a plate slidably engaged with the teeth, means for holding the plate upon the upper portions of the teeth, upwardly extending beveled pins carried by the plate, a plunger slidably mounted upon the head and having beveled faces for engagement of the beveled faces of the pins to move the pins downwardly when the plunger is moved, and means for holding the plunger yieldably against movement to move the pins downwardly.

2. The combination with a curry comb, of a plate slidably engaged with the teeth, flat springs disposed upon the plate, upwardly extending pins disposed upon the springs, stems carried by the pins and engaged through the springs, and through the plate, slideable connections between the ends of the springs and the head of the curry comb, said pins being slideable through the head of the comb and having beveled upper portions, a

casing mounted upon the head of the curry comb, a plunger slidably mounted in the casing and having beveled faces for engagement of the beveled faces of the pins to move the pins and plate downwardly and a spring arranged to hold the plunger normally in inactive position.

In testimony whereof I affix my signature, in presence of two witnesses:

CHESTER MAYR.

Witnesses:
